UNITED STATES PATENT OFFICE.

ALFRED A. OLSON, OF RIVERSIDE, ILLINOIS.

LOCOMOTIVE DRIVING MECHANISM.

1,307,142.

Specification of Letters Patent. Patented June 17, 1919.

Application filed April 1, 1918. Serial No. 225,927.

To all whom it may concern:

Be it known that I, ALFRED A. OLSON, a citizen of the United States, and a resident of the town of Riverside, in the county 5 of Cook and State of Illinois, have invented certain new and useful Improvements in Locomotive Driving Mechanism; and I do hereby declare that the following is a full, clear, and exact description of the same, 10 reference being had to the accompanying drawings, and to the numerals of reference marked thereon, which form a part of this specification.

It has been customary in locomotive construction to connect the rear end of the 15 main rod to a main crank pin to which one of the side rods is also connected; this construction applies the driving force directly to the main crank pin and due to the friction 20 of the main and side rods thereon, the main crank pin soon becomes worn and requires replacement.

This invention relates to an improved 25 form of a locomotive driving mechanism wherein the rear end of the main rod is connected to an intermediate non-revolving crank pin supported by the rear side rod, instead of being connected to the main crank pin, thus affording a construction wherein 30 the main crank pin is relieved of the main driving stress which is exerted upon the intermediate crank pin on which the frictional wear is less than that exerted on the main crank pin when the main rod is attached 35 thereto.

It is an object of this invention to provide an improved form of a locomotive drive transmission mechanism in which the main crank pin is relieved of receiving the 40 drive directly from the main rod.

It is also an object of this invention to provide a locomotive driving mechanism wherein the main rod is connected to a stationary intermediate crank pin.

45 A further object of the invention is the construction of a locomotive driving mechanism wherein the front side rod and the main rod are connected to an intermediate crank pin instead of to the main crank pin.

50 It is furthermore an object of the invention to provide a locomotive driving rod mechanism in which a drive is transmitted from an intermediate crank pin through the

side rods to the main, front and rear crank pins.

55 It is an important object of this invention to provide an improved form of a locomotive driving rod mechanism of simple construction whereby the friction wear from the main rod exerted on a stationary intermediate crank pin to which it is connected is materially less than the wear exerted by the main rod on a revoluble main crank pin when it is connected thereto.

60 Other and further important objects of this invention will be apparent from the disclosures in the specification and drawings.

The invention (in a preferred form) is illustrated in the drawings and hereinafter 70 more fully described.

On the drawings:

Figure 1 is a side elevation of a locomotive equipped with an improved form of a driving rod mechanism embodying the principles of this invention.

Fig. 2 is an enlarged side elevation of the driving rod mechanism showing fragmentary parts of the locomotive driving wheels.

Fig. 3 is a top plan view thereof, with 80 the driving wheel parts omitted.

Fig. 4 is an enlarged detail section taken on line 4-4, of Fig. 3, showing parts in elevation.

Fig. 5 is a side elevation of a modified 85 form of the device shown attached to locomotive driving wheels which are partly broken away.

Fig. 6 is a top plan view thereof with the wheel parts omitted.

90 As shown on the drawings:

The reference numeral 1, indicates as a whole a locomotive provided with front, intermediate or main, and rear driving wheels numbered 2, 3 and 4, respectively, and with front truck wheels 5, positioned on the front truck below steam cylinders 6. Piston rods 7, of said cylinders have the outer ends thereof connected with crosshead wrist pins 8, which are carried by crossheads 9, slidably mounted in the regular way in crosshead guides 10, secured upon the sides of the locomotive. Integrally formed on each of the driving wheels is a 100 crank 11.

105 Mounted at right angles on the front,

main and rear cranks 11, are outwardly extending front, main and rear crank pins 12, 13 and 14 respectively. Rotatably mounted on the rear crank pin 14, is the rear end 5 of a rear side rod 15, on the front end of which is integrally formed a transversely passaged head 16, having parallel forks or lugs 17, integral therewith, each of said forks provided with a tapered passage or 10 opening. Projecting through the tapered openings in the forks 17, is a stationary front intermediate crank pin comprising a body portion 18, a head 19, a tapered portion 20, between said head and body portion, a tapered portion 21, integral with the other end of the body portion 20, and a threaded stud 22, integral with the end of the tapered body portion 21. As clearly shown in Fig. 4, the tapered portion 20, seats in the 15 tapered opening in the inner fork 17, while the tapered portion 21, seats in the tapered opening in the outer fork 17, to position the body portion 18, between said forks. The intermediate crank pin is held in position 20 by means of a nut 23, threaded on the stud 22.

Rotatably mounted on the body portion 18, of the non-revolving intermediate crank pin and adjacent the inner fork 17, is the 25 rear end of a front side rod 24, provided with a bushing 25, which bears upon said body portion. The front end of the front side rod is rotatably mounted on the front end crank pin 12. Also rotatably mounted 30 on the body portion 18, of the intermediate crank pin between the outer fork 17, and the rear end of the front side rod 24, is the rear end of a main rod 26, which is provided with a bushing 27, which bears upon the 35 body portion 18, of the intermediate crank pin. The front end of the main rod 26, is connected to the crosshead wrist pin 8, and is retained thereon by means of a nut 28, removably threaded onto said crosshead 40 wrist pin. The side rods 15 and 24, are held in position upon the crank pins 12, 13 and 14, by means of retaining nuts 29, removably threaded upon the outer ends of 45 said crank pins.

50 In the modified form of the device shown in Figs. 5 and 6, the rear end of a rear side rod 30, is rotatably connected to the rear end crank pin 14, while the front end of said rear side rod 30, is rotatably connected on 55 the main crank pin 13. Integrally formed on the front end of the rear side rod 30, is an apertured tongue or lug 31, which is disposed between the apertured forks of a stub end fork 32, integrally formed on the rear end of a front side rod 33, the front end of which is rotatably connected to the front crank pin 12. The stub end fork 32, is held 60 associated with the lug 31, by means of a front intermediate crank pin 34, provided 65 with a retaining nut 36. The side rods 30

and 33, are retained in position on the crank pins 12, 13 and 14, by means of retaining nuts 37. The rear side rod 30, has integrally formed intermediate the ends thereof an enlarged passaged portion 38, through which 70 projects a non-revolving rear intermediate crank pin 39, to which the rear end of a main rod 40, is pivotally connected. The front end of said main rod 40, is pivotally connected to the crosshead wrist pin 8. 75

The operation is as follows:

In the form of the device shown in Figs. 1 to 4 inclusive, the rear ends of the front side rod and of the main rod are both pivotally connected with the non-revolving front 80 intermediate crank pin. With the parts assembled as described, a drive from the piston rod 7, is transmitted to the crosshead 9, which slidably reciprocates in the crosshead guide 10. Movement of the crosshead in its 85 guide causes actuation of the main rod 26 connected with the crosshead wrist pin 8. The drive is thereby transmitted to the intermediate crank pin, which in turn actuates the side rods 15 and 24, which act to rotate 90 the driving wheels 2, 3 and 4, to move the locomotive. It will be seen that with the main rod connected to the intermediate crank pin, that the main crank pin 13, is relieved from receiving a direct stress from the main 95 rod, and that the frictional wear on the non-revolving intermediate crank pin caused by movement of the main rod thereon is small and materially less than the frictional wear on the rotatable main crank pin in a construction in which the main rod is connected 100 directly to the main crank pin. The reduced amount of frictional wear on the intermediate crank pin is due to the fact that said intermediate crank pin is non-revolving and 105 that the rear end of the main rod has less movement on said intermediate crank pin than it has on the rotatable main crank pin when it is connected thereto.

The operation of the modified form of the 110 driving rod mechanism of Figs. 5 and 6, is very simple, the drive from the cylinder being transmitted through the main rod 40, to the rear non-revolving intermediate crank pin 38, which is supported by the rear side 115 rod 30, thus relieving the main crank pin 13, of the direct driving stress. The rear intermediate crank pin serves as a means for transmitting the drive to the side rods which in turn operate the driving wheels of the 120 locomotive.

In the constructions shown it will be noted that the main rods are connected to non-revolving intermediate crank pins, as are also the front side rods, leaving the main 125 crank pins to act as a support for the front ends of the rear side rods only, thereby preventing said pins from becoming worn too quickly and also relieving the same of direct stresses received from the main rods, which 130

stresses are applied to the non-rotatable intermediate crank pins on which the frictional action of the main rods is less than it is on the main crank pins when the main rods are 5 connected directly thereto, due to a reduced amount of movement of said main rods on the intermediate crank pins.

I am aware that numerous details of construction may be varied through a wide 10 range without departing from the principles of this invention, and I therefore do not purpose limiting the patent granted otherwise than necessitated by the prior art.

I claim as my invention:

15 1. A locomotive driving rod mechanism comprising side rods, a non-revolving intermediate crank pin connected therewith, and a main rod connected with said intermediate crank pin.

20 2. The combination with a main rod, of an intermediate crank pin supporting one end thereof to receive a drive therefrom, main and end crank pins, side rods connected thereto and to said intermediate crank 25 pin adapted to be driven by said main rod through said intermediate crank pin.

30 3. In a locomotive driving rod mechanism the combination with a main crank pin, side rods supported thereby, an intermediate crank pin rigidly secured against rotation on one of said side rods, and a main rod connected to said intermediate crank pin.

35 4. The combination with side rods, of a main and end crank pins supporting said side rods, an intermediate crank pin supported by one of said side rods, and a main rod connected thereto adjacent the other of said side rods.

40 5. The combination with locomotive driving wheels and the cranks thereof, of crank pins on said cranks, a front side rod and a rear side rod supported on said crank pins, a main rod, and an intermediate crank pin for supporting one end of said main rod 45 and said front side rod.

50 6. In a mechanism of the class described the combination with a rear side rod, of crank pins supporting the ends thereof, a front side rod, a crank pin supporting one end thereof, an intermediate crank pin supported on said rear side rod to afford a support for the other end of said front side

rod, and a main rod having one end thereof also connected with said intermediate crank pin.

55

7. In a locomotive driving rod mechanism, a rear side rod, a rear crank pin supporting the rear end thereof, a main crank pin supporting the other end of said rear side rod, forks on the front end of said rear side rod, 60 an intermediate crank pin projecting through said forks, a front side rod, a front crank pin supporting the front end thereof, the rear end of said front side rod connected to said intermediate crank pin, and a main 65 driving rod having one end thereof connected to said intermediate crank pin and the other end connected to receive a drive from a cylinder of the locomotive.

8. The combination with a rear side rod, 70 forks thereon having tapered openings therein, a crank pin projecting through said forks provided with tapered portions near the ends thereof to seat in said tapered openings, means for holding said crank pin 75 in position, and a front side rod and a main rod connected to said crank pin between the tapered portions thereof.

9. In a locomotive driving rod mechanism the combination with a main rod, of a non- 80 revolving intermediate crank pin for supporting one end thereof.

10. The combination with a main rod, of a non-revolving intermediate crank pin supporting one end thereof to receive a drive 85 therefrom, main and end crank pins, side rods connected thereto adapted to be driven by said main rod through said non-revolving intermediate crank pin.

11. In a locomotive driving rod mechanism the combination with a rotatable main crank pin, side rods supported thereby, an intermediate crank pin rigidly secured against rotation in one of said side rods, and a main rod pivotally connected on said non- 90 revolving intermediate crank pin.

In testimony whereof I have hereunto subscribed my name in the presence of two subscribing witnesses.

ALFRED A. OLSON.
